UNITED STATES PATENT OFFICE

96,003

DESIGN FOR A PAVING BLOCK

Francisco Belda, Benicalap, Spain

Application November 8, 1934, Serial No. 53,930
In Spain August 16, 1934

Term of patent 14 years

To all whom it may concern:

Be it known that I, Francisco Belda, a citizen of the Republic of Spain, residing at 20, Rosales Street, Benicalap, Province of Valencia, Spain, have invented a new, original, and ornamental Design for Paving Blocks, of which the following is a specification, reference being had to the accompanying drawing, forming part thereof.

I claim:

The ornamental design for a paving block, as shown.
